UNITED STATES PATENT OFFICE

122,218

DESIGN FOR A PIN

Willard Markle, New York, N. Y.

Application July 27, 1940, Serial No 93,975

Term of patent 3½ years

To all whom it may concern:

Be it known that I, Willard Markle, a citizen of the United States, residing in the city of New York, county of New York, State of New York, have invented a new, original, and ornamental Design for a Pin, of which the following is a specification, reference being had to the accompanying drawing, forming part thereof.

Fig. 1 is a plan view of a pin showing my new design.

Fig. 2 is a side view thereof.

I claim:

The ornamental design for a pin, as shown.

WILLARD MARKLE.
